J. Q. SHERMAN,
AUTOGRAPHIC REGISTER,
APPLICATION FILED MAY 10, 1916.

1,372,460.

Patented Mar. 22, 1921.

UNITED STATES PATENT OFFICE.

JOHN Q. SHERMAN, OF DAYTON, OHIO, ASSIGNOR TO THE STANDARD REGISTER COMPANY, OF DAYTON, OHIO, A CORPORATION OF OHIO.

AUTOGRAPHIC REGISTER.

1,372,460.

Specification of Letters Patent. Patented Mar. 22, 1921.

Application filed May 10, 1916. Serial No. 96,471.

To all whom it may concern:

Be it known that I, JOHN Q. SHERMAN, a citizen of the United States, and a resident of the city of Dayton, in the county of Montgomery and State of Ohio, have invented certain new and useful Improvements in Autographic Registers, of which the following is a full, clear, and exact description, reference being had to the accompanying drawing, forming part of this specification.

My invention relates to improvements in autographic registers for making duplicate written copies of transactions, particularly for use for bills of lading and sales slips and the like in which each of the copies is printed with lines or other printed matter where it is desired to maintain an accurate and perfect registration of the printed matter and the lines of entry as the strips are fed from the machine. It has been found impossible to maintain accurate and perfect registration for a plurality of duplicate strips where the strips are mounted in rolls and fed in clamped relation from the machine to be severed or stored in the machine as may be desired.

It has been supposed that the failure of registration of the undermost strips with reference to the top sheet was due to inaccuracy of feed, and this to a certain extent is the reason for lack of proper registration in many cases. In order to overcome the difficulty, it has been thought that if the strips as they are fed from the machine could be held tightly together and prevented from slipping, the failure to register would be entirely overcome. For this reason, efforts have been made in various ways to insure the feed of the strips of paper from the machine without allowing them to slip, and it has been thought that if the strips could only be fed without slipping, they were bound to be kept in registration.

Notwithstanding all efforts, however, to prevent slipping, it is found that registration cannot be maintained.

I have discovered that one reason for this failure is inherent in the paper material as well as in the devices for feeding the same. The paper strips are printed with lines and other printed matter upon wide sheets of paper run through the press so that a plurality of forms are simultaneously printed, and then the wide sheet is slit into the

widths desired and the several strips mounted in the register. 55

The paper sheet, however, upon which the printing and lining is done, is to a certain extent elastic. In running through the press it will be longer on one edge than on the other, and there will be a sagging at some portions of the sheet, and the sheet will be taut at other portions. While the punches and type in any form of press are in exact alinement and the punches and lines the same distance apart, when the punching is performed on a flat surface, the punching and printing is done as a unit and after one ticket or slip is printed and punched, the throw of the press will cause inaccuracy for the next slip, that is to say, the sag or tautness between each slip as it is impressed will cause a variation in distance between the next series of openings and the first set. With a cylinder press and punching mechanism the variation in distance of the openings and the lines will be apt to occur at any point in the series and not merely between each series. It results from this, that, although the lines are printed accurately, when the strips are matched up in the register for copies, as the strips are unwound, no matter how securely they are held together to prevent slipping, proper registration cannot be maintained. 85

What is required, therefore, to obtain a proper registration throughout a long series of printed slips which have been superimposed on each other and printed with lines which it is desired to maintain always in accurate alinement, is to recognize that the difficulty experienced is due not only to inaccuracy of feed, but to the character of the paper material, and as each set of tickets or slips are severed, to arrange for a readjustment during the feeding operation. 95

As the first set of slips are severed, the lower end of the strips will be slightly out of register, and to prevent this slight error from accumulating, so that in a very short length the strips are entirely out of register, it is necessary to adjust for each separate operation.

It is the object of my invention to provide means for accomplishing this adjustment of the slips between each operation, and I have applied my invention to the type of register such as is shown, for example, in the

Schirmer Patent No. 940,481, of November 16, 1909, wherein the tapered feeding pins readily enter the holes in the paper, but in which no looseness of the paper on the pins, 5 once engagement is made, is provided for.

In the drawing,

Figure 1 is a side elevation of my improved register, partly in section.

Fig. 2 is a top plan view of one corner of 10 the register.

Fig. 3 is a perspective view, much enlarged, illustrating the method of feeding the strips.

Fig. 4 is a detail side view of one of the 15 feeding pins illustrating the adjustment of the strips.

Fig. 5 is a detail, much enlarged, of one 20 edge of the paper strips showing the openings in the superimposed strips out of alinement.

The register consists of the usual case 1, with top plate 2, under which the paper strips from the three rolls 3, 4 and 5 are fed over the writing tablet with carbon paper 25 interposed between the strips for duplicate copies. The method of feeding the paper is by means of a pair of sprocket wheels 6, at the edges of the strips, mounted on the shaft 7 journaled in the casing and rotated 30 by the crank handle 8. The two sprocket wheels are provided with the pins 9, spaced around the periphery of the wheels with the pins preferably of conical or slightly conical shape.

35 The paper for use in the machine is especially prepared by punching or cutting the holes 12 at uniform distances apart, and with the holes or openings along each side of each strip in exact alinement with each 40 other. The holes are formed at the same time that the strips are printed with the lines and printing matter, and the line and holes must be printed with accurate uniformity. The pins 9 are spaced on the disks 45 to correspond with the holes, and to carry out my invention it is necessary that the diameter of the holes or openings in the paper strips shall be considerably greater than the diameter of the pins. In other words,

50 the pins must fit very loosely in the openings. The cover plate 2 which covers the paper strips 13, 14 and 15 and keeps them in contact with the feeding pins, is provided with a raised segmental portion 16, leaving free space 17 for the passage of the pins; while at the same time the cover plate 55 extending over the strips holds them in contact with the feeding pins, but only loosely in contact. When the desired length of 60 strip and duplicate copies has been fed from the machine, they are torn off against the front edge 18 of the cover plate, or a separate fixed blade secured to the casing can be used for tearing off the strips. There is no 65 tension, however, on the paper strips other

than such as is necessary to hold them in contact with the sprocket wheels either during the feeding operation or while they are being torn off against the tearing edge 18. The reason for this is that it is essential 70 that with each operation of the machine, the strips may adjust themselves while they are being fed.

Instead of a roller feed, or a feed of gripping fingers, or even a sprocket wheel 75 feed with the sprocket pins fitting tightly in the openings prepared for them in the paper strips, the paper is fed forward by the pins engaging the forward edge of the respective holes as indicated in Fig. 4, and 80 thus pushing the paper. The effect of this is that the strips are lined up, so to speak, and any lack or registration is corrected in much the same way that sheets of paper are alined by holding them loosely in vertical 85 position and tapping them on a table or support.

The essential feature of my invention consists in this loose feeding of the paper strips by pushing against them at the forward 9 edge of the respective holes, as the wheels with the projecting pins are rotated.

The error in registration of the lines on the respective superimposed strips is of course very slight for the length of the single slips or tickets when they are severed from the web. But unless provision is made for adjustment during the forward feed of the paper during the next succeeding operation, the error at the commencement of 100 the operation accumulates, and the essential feature of my discovery resides in the recognition of the necessity of readjustment for alinement purposes during each feeding operation, and the construction devised to accomplish this result is to provide the openings in the strips of larger diameter than the diameter of the feeding pins, and then to arrange for a loose contact between the respective webs so that the pins as they advance and enter the openings will shift the paper slightly to bring the holes in exact 110 alinement.

This correction of the error for each particular slip as the feed progresses, enables 115 me to produce a register in which perfect alinement can be maintained throughout the entire length of the respective webs of paper, and it will be noted in this connection that these webs are frequently two hundred or 120 three hundred feet or more in length.

It is not of the essence of the invention that the holes should be circular and the feeding pins cylindrical, because some other shape of opening with pins to correspond 125 would apparently accomplish the same result, but it is preferable to provide circular openings, as the pins can more readily enter and withdraw from circular holes.

By "diameter" in the claims that follow, 130

the dimension referred to is the cross sectional dimension of the pins in the direction of the feed, and this is the case also for the holes in the paper. It is the diameter extending in the direction of the feed that is referred to.

Having thus described my invention, what I claim as new and desire to secure by Letters Patent, is:—

- 10 1. In an autographic register, a feeding mechanism for the superimposed paper strips, comprising a plurality of series of radial pins, and means for rotating them to engage in successive correspondingly spaced openings in the paper strips, said openings being of substantially larger diameter than the diameter of the pins, whereby the registration of the openings may be continuously maintained as the strips are fed.
- 15 2. In an autographic register, a feeding mechanism for the superimposed paper strips, comprising a plurality of series of uniformly spaced radial pins, and means for rotating them to engage in successive correspondingly uniformly spaced openings in the paper strips, said openings being of substantially larger diameter than the diameter of the pins, whereby the registration of the openings may be continuously maintained
- 20 30 as the strips are fed.
- 25 3. In an autographic register, a feeding mechanism for the superimposed paper strips, comprising a plurality of series of radial pins, and means for rotating them to engage in successive correspondingly spaced openings in the paper strips, said openings being of substantially larger diameter than the diameter of the pins, with the superimposed paper strips in loose contact with
- 35 40 each other, and means for maintaining their engagement with the pins.
- 45 4. In an autographic register, a feeding mechanism for the superimposed paper strips, comprising a plurality of series of uniformly spaced radial pins, and means for rotating them to engage in successive correspondingly uniformly spaced openings in the paper strips, said openings being of sub-

stantially larger diameter than the diameter of the pins, with the superimposed paper strips in loose contact with each other, and means for maintaining their engagement with the pins.

5. In a machine of the character described, means for feeding a plurality of webs of paper having corresponding series of holes therein, comprising means for pulling said webs of paper in registry with each other, for duplicate writing past a writing point comprising a rotary actuated element provided with tapering pins having a base of substantially smaller gage than the holes in the webs.

6. In a machine for making duplicate copies on a plurality of webs of paper having corresponding series of holes therein, a feeding sprocket for pulling said webs past a working point having sprocket pins adapted to loosely engage at all points in the holes in the webs.

7. In a machine of the character described, a plurality of webs of paper having corresponding series of holes therein, and a feeding sprocket for said webs having sprocket pins tapering to a blunt point and having a base of substantially less diameter than the holes.

8. In a machine of the character described, means for feeding a plurality of webs of paper having corresponding series of holes along the side margins thereof, comprising a pair of jointly operated sprockets for feeding the webs, located marginally of the webs, having sprocket pins of substantially less diameter than the holes in the paper, and adapted to successively engage the holes.

9. In a machine for making duplicate copies on a plurality of webs of paper, said webs printed alike, and having perforations therein spaced exactly with the printing, a feeding sprocket for pulling said webs past a working point having sprocket pins adapted to loosely engage at all points in the holes in the webs.

JOHN Q. SHERMAN.
